United States Patent

Des. 242,476
Patented Nov. 23, 1976

242,476

COVER FOR AN AQUARIUM OR THE LIKE

Carol T. Beckman, 3200 College Ave.,
Quincy, Ill. 62301

Filed Apr. 22, 1975, Ser. No. 570,441

Term of patent 14 years

Int. Cl. D30—02

U.S. Cl. D30—12

FIG. 1

FIG. 2

FIG. 3

FIG. 4

FIG. 1 is a front elevational view of a cover for an aquarium or the like showing my new design, the bottom of which is plain and unornamented;

FIG. 2 is a top plan view;

FIG. 3 is a right side elevational view; and

FIG. 4 is an enlarged rear elevational view.

I claim:

The ornamental design for a cover for an aquarium or the like, as shown and described.
